UNITED STATES PATENT OFFICE.

WILLIAM O. EAKIN, OF INDIANAPOLIS, INDIANA, ASSIGNOR OF ONE-HALF TO HENRY J. HERT, OF INDIANAPOLIS, INDIANA.

VEHICLE-TOP.

1,151,930.

Specification of Letters Patent. Patented Aug. 31, 1915.

Application filed August 22, 1912. Serial No. 716,401.

To all whom it may concern:

Be it known that I, WILLIAM O. EAKIN, a citizen of the United States, residing at Indianapolis, Marion county, and State of Indiana, have invented and discovered certain new and useful Improvements in Vehicle-Tops, of which the following is a specification.

My invention relates to vehicle tops and 10 more particularly to means for securing the back of the top to the body of the vehicle.

The object of the invention is to provide 15 means of connection between the bow of the top and the body of the vehicle which shall be rigid and unyielding in the line of strain, which may be readily adjusted to accommodate 20 said connecting means to variations in the distance between the body and the bow of the top to be attached thereto or to compensate 25 for stretch or flexion in the body or bow after use, which may be rigidly and securely fixed in fastening position after adjustment and which may be so mounted on the top as to be concealed within the fabric thereof.

With these ends and others in view, my invention is embodied in preferable form in the construction and arrangement herein-after described and illustrated in the accompanying drawings.

In the drawings, Figure 1 is a rear view in elevation of a portion of a vehicle body and a portion of the top, with the fabric partly broken away to show the connecting strap; Fig. 2, a vertical longitudinal section through the strap and top and strap fastener; Fig. 3, a cross section on line 3—3 of Fig. 1; Fig. 4, a detail enlarged section through the strap fastener at right angles to Fig. 2, and with the strap secured; Fig. 5, a view similar to Fig. 4, with the strap in engagement with the fastener, and Figs. 6 and 7, a detail elevation and sectional view of a modified form of fastener.

Referring to the drawings, 1 is the body 45 of the vehicle, 2 the fabric of the top and 3 the bow of the frame of the top, which extends across the upper rear end of the latter. The fabric of the top, as is usual, is made 50 in two layers or plies united, and between these layers is formed a vertical pocket 4 extending from the bow 3 to the lower edge of the fabric and open at its lower end. A metallic strap 5, made preferably of a thin, 55 pliable strip, is permanently secured by nails or screws 6 at its upper end to the bow

3 and the strap extends through the pocket 4 and is concealed thereby throughout the vertical length of the fabric, and projects out through the open lower end of the 60 pocket. At its lower end this strap is doubled back upon itself to provide a loop 7. Owing to the extension of the strap afforded by the loop and the pliability of the metal of the strap, the effective length of the latter 65 may be increased or shortened by bending the straps at different points and thus lengthening or shortening the loop.

The loop 7 is adapted to engage a tongue or cross bar 8 mounted in a clamp. This 70 clamp consists preferably of an integral looped or doubled section of metal and comprising a base strip 9 bearing against the body of the vehicle and an outer clamping plate or strip 10. The cross bar or tongue 8 75 is preferably made separate and removable from the clamp and is preferably provided with a bur or corrugation 11 adapted to engage a corresponding depression in either the limb 9 or limb 10 of the fastener clamp, 80 whereby the tongue is removably attached to the clamp member, so that the two parts may be more readily handled, and may be applied together to the vehicle body. Screws 12, 13, pass through the two limbs of 85 the clamp member and the tongue and into the body of the vehicle. The screw 13, which engages the separated ends of the clamp members 9 and 10 serves as a pressure means to clamp the outer member 10, the strap, the 90 tongue and the base member together.

The arrangement above described is shown in Figs. 1 to 4 inclusive and in this form of the device the lower end of the metal strap is adapted to be passed through the clamp, 95 between the inner limb 9 and the tongue 8 and then bent back over the tongue and carried up between the tongue and the outer limb. Thereupon the screw 13 is screwed down, 100 pressing the outer member 10 against the strap, so as to clamp the latter and prevent the loop from bending open and aid the tongue in gripping the strap. To further add to the clamping action on the loop a set screw 14 may be provided which engages 105 and passes through the outer clamping plate 10 and the inner end of which bears against the loop of the strap.

In Figs. 6 and 7 a modified form of strap fastener is shown in which the pliable strap 110 here numbered 15 is not looped or doubled at its end but has its free end adapted to ex-

tend between the two clamping members 16, and 17 of a metallic clamp body. The separated ends of the clamp are adapted to be connected and the outer clamp member 5 pressed against the strap by means of an adjusting screw. The inner face of the outer clamp member 17 is provided with inwardly projecting burs or corrugations 19, which are opposite corresponding depressions or recesses in the inner member 16, by which means when the outer pressure member is screwed down against the strap, these burs or corrugations will be caused to bite against and into the surface of the strap, thus tightly clamping the latter in place. To adjust the strap to the top and body, in the form of device shown in Figs. 5 and 6, the end of the strap is drawn through the clamp until the proper adjustment of the 10 top relative to the body is obtained, then the strap clamped in place, and the excess end portion of the strap cut off or bent up, upon itself.

In vehicle tops, especially in automobile tops, difficulty has been experienced heretofore in obtaining the proper fit and adjustment between the top and the body of the vehicle. It frequently happens that, owing 25 to variations in size of the bodies and variations in the form of the frame of the top, that the strap or similar means employed to connect the bow of the top to the body of the vehicle is not of the exact length required to rigidly connect these parts. It has 30 been usual to employ a leather strap for each connecting means, which strap has been provided with an adjusting buckle between its ends. These leather straps, it has been found, will frequently break when attaching 35 the top to the body and subjecting the strap to the severe stretching strain necessary to be applied to obtain the relative rigidity between bow and body and also owing to the counter strain imposed by the 40 front straps. If it is necessary to take up the strap in length in adjusting it to the top, the buckle used in the leather strap does not afford a close degree of adjustment and hence the desired rigidity will not be attained. The strap also is subjected to great 45 strain in use due to the shocks imparted to the top from the body of the vehicle. Such leather strap is also objectionable in respect to its appearance and as an obstruction.

50 With my invention consisting of the metallic strap, unyielding longitudinally, but pliable, so as to yield with the transverse folding of the fabric and so as to permit manipulation of the strap for adjustment, a strong inherently adjustable fastener strap is provided, which can be adjusted to any degree, and which in conjunction with the pocket-bearing fabric, affords a con-

struction in which no part of the connecting means appears to view or offers any obstruction. 65

It is clear that changes in the detail of the embodiment of my invention, within the scope of the appended claims, may be made without departure from the principle of the 70 invention.

Having thus described my invention what I claim is,

1. In combination with a vehicle top, a flat pliable strap adapted to connect the 75 upper rear bow member of the top and the body of the vehicle, said strap having its lower free end doubled upon itself to form a loop and frictional fastening means on the vehicle body having a member around which 80 said loop passes and having means to force said member into frictional gripping contact with the surfaces of the looped portions of the strap, substantially as described.

2. In combination with a vehicle top, a 85 flat pliable metallic strap adapted to connect the bow of the top and the body of the vehicle, and having its lower end doubled back on itself to form a loop, fastening means for said strap on the vehicle body, 90 comprising frictionally clamping members operable to receive between them and clamp said strap and a cross member adapted to engage said loop, substantially as described.

3. In combination with a vehicle top and 95 its bow, a flat, metallic strap adapted to connect said bow and the body of the vehicle and rigidly connected at its upper end to the bow and its other end free and having a looped lower end and fastening means 100 on the vehicle body having clamping members and a separate member detachably secured to said fastening means, and adapted to engage the loop of said strap, substantially as described. 105

4. In combination with a metallic connecting strap doubled at one end to form a loop, fastening means therefor consisting of an integral body of metal having folded clamping members at one end and adapted 110 to receive between them the lower end of the strap, and a tongue parallel to said clamping members detachably clipped to said fastening means, and operable to engage said loop of the strap, means to force 115 said clamping members, strap and tongue together, substantially as described.

In witness whereof, I have hereunto set my hand and seal at Indianapolis, Indiana, this 19th day of August, A. D. nineteen 120 hundred and twelve.

WILLIAM O. EAKIN. [L.S.]
